JACQUARD MACHINE

John Thomas Hardaker, Bradford, England

Application May 2, 1934, Serial No. 723,531
In Great Britain May 4, 1933

7 Claims. (Cl. 139—90)

In the weaving of fine and delicate fabrics, such as of silk, artificial silk, fine cotton or the like, by jacquard machines having the usual and ordinary harnesses or cords, great inconvenience and many defective results are encountered by the curling and twisting actions of the said cords causing the warp threads to encircle and become entangled with the mails and their supports or attachments, whether same are of the well known metal type or of the fibrous cord formation. The said curling and twisting actions are most frequently met with when a change in the hygroscopic conditions of the atmosphere occurs, such for example as when the atmosphere changes from being comparatively dry to a condition in which there is sufficient moisture therein for the harness cords to absorb same, as is well understood.

My present invention consists in the production and application of means whereby said curling, twisting and other entangling actions of the harness cords are entirely prevented from imparting any detrimental motion or movement to the mails or members through which the warp threads pass, that will interfere with their effective operations.

The accompanying sheets of drawings are illustrative of my invention and are hereinafter referred to, in order that same may be readily understood:—

Fig. 1 is a front view showing a group of harness cords in the respective position which each one of them occupies in the front row of a comberboard, and each with its attachments to the mail which it operates and to the lingo or weight which effects its descending movement.

Fig. 2 is a side view of a like group of said harness cords in their respective positions from the one in front to those which are successively adjoining and in staggered positions behind. The mail and lingo or weight on each harness cord are shown in the respective positions that they occupy according to my invention.

Fig. 3 is a sectional plan of a group of lingos or weights occupying their respective and relative positions as they are suspended from their harness cords when these latter are being held and guided in their several vertical paths by the comberboard. The lingos or weights shown by this figure are of the cross sectional shape hereinafter described.

Figs. 4 and 5 are similar views to Fig. 3 but show modified forms or shapes of the lingos or weights hereinafter explained.

Figs. 6 and 7 are similar views to Figs. 1 and 2 respectively but are drawn to a reduced scale so

that a portion of the comberboard may, in each case, be shown in its relative position to the harness cords and the members attached thereto and operated by said cords.

In carrying my invention into effect I make use of metal mails *a* which are preferably fixed upon wire connections *b*, *b*¹ that reach from their attachments to the harness cords *c* in proximity to the under surface of their guiding member *d* (styled the comberboard) down to their attachments to the lingos or "harness weights" *f*, although my said invention might be less effectively made use of in connection with the ordinary harness cords *c* wherein the said cords reach to the metal mails *a* or in which the said mails *a* have additional cords instead of the metal wires *b*, *b*¹, to connect them to the lingos or weights *f* in a manner which is common and well known.

To the lower end of each wire member *b* I couple its respective lingo *f*, preferably by an elongated metal link *g* taking through the loop *a*² on the end of the member *b*, as well as taking through the opening *g*¹ in the end of the lingo *f*, since the said form of link engages with the loop *a*² in a better manner for controlling and preventing any swivelling actions being transmitted thereto than would a link of an annular or like shape. Further, by the link *g* taking through the opening *g*¹ in the upper end of the lingo *f*, the weight of said lingo *f*, acting through the link *g* and member *b*, will more effectively retain the mail *a* with its opening in axial alignment with the path through which the thread of warp *h* (which it has to operate) extends. Thus when the opening for its thread of weft *h* is retained with its axis in said alignment, a perfectly free and clear course for the passage of the warp through same is secured.

Each of the lingos *f* I now form, according to my invention, of the flattened (or other shape than cylindrical in cross section) as is shown by Figs. 3, 4, and 5; thus each lingo is prevented from moving more out of its path than into a position where it can touch or come in contact with one or other of its neighbouring lingos. That is to say, taking the two lingos 2 and 3 of Fig. 3, these, if slightly oscillated about their vertical axes (as is shown in broken lines), would come into contact with each other on the line of contact 4, or if oscillating in the opposite direction, then the line of contact would be where the lingo 5 was contacted with by the lingo 3, or where the lingo 5 might contact with the lingo 6 or 7 as will be understood.

It will be observed that the staggered arrange- 55

ment of the lingos, which is common and well known, facilitates the employment of the flattened form of lingo which, by its flattening, is caused to have its breadth extended, while its thickness is shortened or diminished. Thus in all cases the lingo is retained with its side surfaces in positions that do not detrimentally permit the opening through the mail *a* being twisted to interfere with the free passage of the warp thread *h*, as is above stated.

As an alternative to the straight flattened formation of lingo shown by Fig. 3, the body of the lingo may be slightly grooved or channelled, as is shown by Fig. 4, in which case the edges of the lingo are broadened so that less oscillation on the part of each individual lingo will be diminished by the space between them being reduced in width. Or again for similar or other reasons the formation of the body of the lingo may be of a double convex form in cross section, as is shown by Fig. 5. In each case the object of the formation is to enable the lingo, so shaped, to prevent its neighbouring lingos from too great an oscillation.

At the ends of the series or group of lingos, guiding bars *k* are used so that those lingos adjoining said guiding bars will be prevented by same from twisting, on account of having neighbouring lingos on one side of them. Again, longitudinal bars *k*¹ may be mounted in the usual framework adjacent the lingos, as is shown by Figs. 3, 6, and 7.

In cases where groups of lingos *f* are made use of, and are arranged to occupy positions in the loom with spaces between them (such as when a fabric is being produced where only sectional parts of the warp have to be operated by the jacquard while all the other intervening warp threads are operated by the ordinary shedding or warp operating devices), then similar cross bars *k* and longitudinal bars *k*¹ are used and respectively mounted adjacent the two end rows of lingos and the front and back rows, as is shown by Fig. 3.

Such being the nature of my said invention, what I claim is:—

1. In jacquard machines, mails or members for receiving and operating warp threads, wire or metal extensions from said mails coupled to the harness cords which are conducted through guiding holes made in staggered positions through the comberboard and secured to the vertical hooks in the jacquard machine, other metal extensions from said mails to couple them to their operating lingos or weights, each of said lingos having a length greater than thickness so that rotary or oscillatory motion about its axis is limited or prevented by its contacting with its neighbouring lingo or lingos for the purpose specified.

2. In jacquard machines, metal mails or members for receiving and operating warp threads, wire or metal extensions from said mails coupled to the harness cords which are conducted by guiding holes made in staggered positions through the comberboard and secured to the vertical hooks in the jacquard machine, other metal extensions from said mails to couple them to their operating lingos or weights, each of said lingos having a length greater than its thickness so that rotary or oscillatory motion about its axis is limited or prevented by its contacting with its neighbouring lingo or lingos, for the purpose specified.

3. In jacquard machines, metal mails or mem-

bers for receiving and operating warp threads, wire or metal extensions from said mails coupled to the harness cords which are conducted by guiding holes made in staggered positions through the comberboard and secured to the vertical hooks in the jacquard machine, other metal extensions from said mails to metal links secured to the lingos or weights, each of said lingos having a length greater than its thickness so that rotary or oscillatory motion about its axis is limited or prevented by its contacting with its neighbouring lingo or lingos for the purpose specified.

4. In jacquard machines, metal mails or members for receiving and operating warp threads, wire or metal extensions from said mails coupled to the harness cords which are conducted by guiding holes made in staggered positions through the comberboard and secured to the vertical hooks in the jacquard machine, other metal extensions from said mails to metal links of elongated shape secured to the lingos or weights, each of said lingos having a length greater than its thickness so that rotary or oscillatory motion about its axis is limited or prevented by its contacting with its neighbouring lingo or lingos for the purpose specified.

5. In jacquard machines, metal mails or members for receiving and operating warp threads, wire or metal extensions from said mails coupled to the harness cords which are conducted by guiding holes made in staggered positions through the comberboard and secured to the vertical hooks in the jacquard machine, other metal extensions from said mails to metal links of elongated shape secured to the lingos or weights, each being of flattened or other shape which makes it of a width greater than its thickness, so that by its said shape rotary or oscillatory motion about its axis is limited or prevented by its contacting with its neighbouring lingo or lingos for the purpose specified.

6. In jacquard machines, metal mails or members for receiving and operating warp threads, wire or metal extensions from said mails coupled to the harness cords which are conducted by guiding holes made in staggered positions through the comberboard and secured to the vertical hooks in the jacquard machine, other metal extensions from said mails to metal links of elongated shape secured to the lingos or weights, said lingos or weights, each having a groove or furrow on one or both of its side surfaces with its outer edges broader or thicker than its longitudinal central part between said edges, so that by its said shape rotary or oscillatory motion about its axis is limited or prevented by its contacting with its neighbouring lingo or lingos for the purpose specified.

7. In jacquard machines, metal mails or members for receiving and operating warp threads, wire or metal extensions from said mails coupled to the harness cords which are conducted by guiding holes made in staggered positions through the comberboard and secured to the vertical hooks in the jacquard machine, other metal extensions from said mails to metal links of elongated shape secured to the lingos or weights, said lingos, each being of double convex shape in cross section, so that by its said shape rotary or oscillatory motion about its axis is limited or prevented by its contacting with its neighbouring lingo or lingos for the purpose specified.
